COMBINED ASH TRAY AND PEN HOLDER
ATTACHMENT FOR TELEPHONES

George A. Aro, 2925 18th Ave. N., Minneapolis, Minn.

Filed Mar. 4, 1964, Ser. No. 78,860

Term of patent 14 years

(Cl. D85—2)

FIG. 1 is a front perspective view of a combined ash tray and pen holder attachment for telephones, showing my new design;

FIG. 2 is a reduced side elevational view;

FIG. 3 is a rear elevational view; and

FIG. 4 is a rear perspective view thereof.

The broken line showing of a telephone in FIGS. 1 and 2 is for illustrative purpose only.

I claim:

The ornamental design for a combined ash tray and pen holder attachment for telephones, substantially as shown and described.
